UNITED STATES PATENT OFFICE.

ELIJAH NEFF, OF ROCHESTER, INDIANA, ASSIGNOR OF THREE-FOURTHS
TO JAMES GILCHRIST, OF LIMA, OHIO, AND ANDREW W. FELTS, OF FULTON
COUNTY, INDIANA.

PUMP.

SPECIFICATION forming part of Letters Patent No. 378,402, dated February 21, 1883.

Application filed June 22, 1887. Serial No. 242,158. (No model.)

To all whom it may concern:

Be it known that I, ELIJAH NEFF, a citizen of the United States, residing at Rochester, in the county of Fulton and State of Indiana, have invented a new and useful Improvement 5 in Pumps, of which the following is a specification.

My invention relates to an improvement in pumps for windmills; and it consists in the peculiar construction and combination of devices, that will be more fully set forth hereinafter, and particularly pointed out in the claims.

The accompanying drawing is a vertical sectional view of a pump embodying my improvements.

A represents a vertical pump-barrel, which is suspended from and has its upper end communicating with the lower end of a vertical 20 tube, B. The said tube is connected to a base-plate, C, that is supported on the platform D.

E represents a vertical tube, which is arranged parallel with the tube B and at a slight distance therefrom, and the said tube E is also 25 connected to the base-plate C. The upper end of the tube E is closed by a cap, F, having an arm, G, that extends to and is connected to the upper portion of the tube B.

H represents a compression-chamber through 30 which the tubes B and E extend. The tube E has a series of perforations, I, which communicate with the lower end of the compression-chamber H, and the said tube is also provided with a stop-cock or faucet, K.

L represents a cap which closes the upper 35 end of the tube B.

M represents a link which has its lower end pivoted to one side of the cap F. The upper end of this link is connected to a lever, N, 40 which has a counterpoised weight, O, at its short end. To the said lever N is connected the upper end of a piston-rod, P, and to the lower end of the said rod is secured a piston, R, that works in the pump-barrel A when the 45 lever N is operated.

The lower ends of the cylinder A and of the pipe E are connected together by a U-shaped coupling-pipe, S. To the lower side of the said coupling-pipe is attached the upper end

of a suction pipe, T, which extends down into 50 the well or other source of water. In the upper end of the suction-pipe is a valve-case, U, in which is located an upwardly-opening valve, V.

W represents a similar valve arranged in the 55 upper end of the coupling-pipe S at the lower end of the tube E.

X represents a pipe which is connected to and communicates with the lower end of the pipe E. The outer end of the pipe X is upturned and arranged vertically, and is provided at its upper end with a faucet or stop-cock, Y, having a goose-neck, Z.

A' represents a vertical pipe which extends from the upper side of the pipe X. The upper 60 end of the said pipe A' is provided with a discharge-nozzle, B', controlled by a stop-cock, C'.

D' represents a compression-cylinder, through which the lower portion of the pipe A' passes, 70 and the said pipe is provided with a series of openings, E', communicating with the interior of the compression-cylinder near the lower end thereof. On the upper end of this cylinder is secured a casing, F', arranged below the 75 stop cocks or faucets K and Y, so as to receive the water discharged from the said faucets.

To the lower side of the pipe X, and communicating with the same between the pipes 80 A' and E, is secured a depending cylinder, G', the lower end of which is closed.

H' represents a piston adapted to reciprocate in the said cylinder, and from the lower side of the said piston extends a piston-rod, I', 85 which passes through an opening in the closed end of the cylinder, and is connected to a vertically-movable yoke or guide-frame, A'. To the upper end of the latter is connected the lower end of the rope or rod L', that is connected to a weighted lever or vane, a, such as are commonly employed to throw a windmill into and out of the wind. The weight on the lever or vane normally keeps the wind-wheel 90 in operation and the yoke K' elevated, so as to 95 elevate the piston H' in the cylinder G'.

The operation of my invention is as follows: The lever N is operated by connecting the

same to the operating rod or pitman of an ordinary windmill. When the piston R rises in the cylinder A, the valve W closes and the valve V opens, a partial vacuum is formed in the lower end of the cylinder A and in the suction-pipe P, and water is drawn upwardly through the latter into the lower end of the cylinder. On the downstroke of the piston the water in the cylinder is forced upward to past the valve W into the pipes X and E. Continued operation of the pump-piston causes water to flow from the pipe E into the compression-chamber H and fill the same, and to flow from the pipe X into the pipe A' and into the compression-cylinder D' to fill the latter. Continued operation of the pump-piston causes the pressure of water in the pipe X to become so great that it forces the piston H' downward in the cylinder G', thereby drawing downward 15 on the guide yoke or loop K', and causing the latter to draw downward upon the rod L', and thereby throw the wind-wheel out of gear and cause it to cease to operate.

When the stop K is opened, water is discharged from the pipe E into the basin, thus 25 relieving the pressure in the compression-chambers H and D', and after a quantity of the water has been drawn into the basin the pressure on the piston H' will become so slight 30 that the counterbalanced lever will cause said piston to rise in the cylinder G', and thereby again start the windmill and the pump in operation.

The chambers H and D' serve to store a 35 quantity of water under pressure and make it accessible at all times by simply opening either or both of the faucets K and Y. When the stop-cock C is opened, the water compressed in the chamber D' will be forced upwardly 40 through the pipe A' and through the nozzle G' in a jet and form a fountain. When the pump is in operation and either or both of the stop-cocks K and Y are opened, water will flow therefrom into the basin in a continuous 45 stream.

Having thus described my invention, I claim—

1. The combination of the cylinder A, the reciprocating piston R therein, the suction-pipe having the valve V, the pipe E, communicating with the suction-pipe and with the cylinder and having the check-valve W, the said pipe being provided, also, with the stop-cock K, the compression-chamber H, communicating with the pipe E, the pipe X, communicating with the pipe E, the cylinder G', communicating with the pipe X, the piston H' in the said cylinder and having the rod I' projecting from the same, for the purpose set forth, the pipes A', communicating with the pipe X, and the compression-chamber D', communicating with the pipe E', all combined and arranged to operate substantially in the manner and for the purpose described. 55

2. The combination of the compression-chamber H, having the cock K, the pipe B, extending down through the compression-chamber, the cylinder A, attached to the lower end of said pipe, the pipe E, extending through the chamber H, communicating therewith at 60 I, and also communicating with the lower end of cylinder A, and having the check-valve W, the inlet-pipe having valve V, the cap F, secured on the projecting upper ends of pipes B and E, the piston R in cylinder A, and having rod P extending upward through pipe B, the link M, attached to cap F, and the handle-lever attached at different points to the upper 65 end of link M and the upper end of rod P, substantially as described. 75

In testimony that I claim the foregoing as my own I have hereto affixed my signature in presence of two witnesses.

ELIJAH NEFF.
